W. S. GATES

DYEING AND BLEACHING MACHINE

Filed April 21, 1924

Fig. 1

UNITED STATES PATENT OFFICE.

WALTER S. GATES, OF DETROIT, MICHIGAN, ASSIGNOR TO INSULATING MATERIALS COMPANY, OF DETROIT, MICHIGAN, A CORPORATION OF MICHIGAN.

DYEING AND BLEACHING MACHINE.

Application filed April 21, 1924. Serial No. 708,028.

To all whom it may concern:

Be it known that I, WALTER S. GATES, a citizen of the United States of America, residing at Detroit, in the county of Wayne and State of Michigan, have invented certain new and useful Improvements in Dyeing and Bleaching Machines, of which the following is a specification, reference being had therein to the accompanying drawings.

- 10 This invention relates generally to dyeing and bleaching machines and refers more particularly to lifting devices for facilitating the removal of the yarn packages from the kiers of such machines.
- 15 One of the essential objects of the invention is to provide the yarn packages with a strong and durable support that is adapted to be moved longitudinally of the yarn holders in the kier to facilitate the removal of 20 the yarn from the kier.

Another object is to provide a support of this type that may be conveniently raised or lowered and that is preferably guided within the kier by suitable means extending upwardly from the bottom of the kier.

25 A further object is to provide effective means for preventing the liquor used for dyeing from escaping at the lower ends of the yarn holders when the support is in lowered position.

With the above and other objects in view, the invention consists of certain novel features of construction, combination and arrangement of parts as will be more fully described and particularly pointed out in the appended claims.

In the accompanying drawing:

Figure 1 is a fragmentary elevation of a kier and showing my lifting device applied thereto;

Figure 2 is a top plan view of the lifting devices;

Figure 3 is an enlarged detail sectional view.

Referring now to the drawing in which like characters of reference designate corresponding parts throughout the several views, the numeral 1 designates a kier of a dyeing machine having a true bottom 2 and a false bottom 3, the latter preferably having vertical openings 4 therein through

which the liquor used for dyeing is supplied to tubular yarn holders 5. As shown, these holders preferably threadedly engage the false bottom and are provided with apertures 6 through which the liquor is adapted to pass for dyeing the yarn packages 7. Any suitable means such as the caps 8 threadedly engaging the holders 5 may be used for retaining the yarn packages 7 in position on the holders during the dyeing operation.

To facilitate the removal of the yarn packages from the kier after the dyeing operation, I preferably provide a grid or plate 8' that normally rests upon the false bottom 3 of the kier beneath the yarn packages and that is adapted to be raised by means of rods 9 extending upwardly from the grid 8' at spaced points thereof. The grid may be any shape or size desired and may be constructed of any suitable material, such as brass, for supporting when raised, the weight of the wet yarn packages resting upon it. As shown, the grid 8' is preferably circular in form and is provided at spaced points with relatively large openings 10 for receiving the upwardly projecting yarn holders 5, while the lifting rods 9 are preferably located between the yarn holders and are threaded into the grid 8' and also into suitable attaching plates 11 that are rigidly secured to the upward face of the grid as shown in Figure 1 of the drawing. When the cover of the kier is raised, any suitable means such as the chains 12 of a suitable hoist may be connected to the eyes 13 at the upper ends of the lifting rods for raising or lowering the grid within the kier.

For guiding the grid while being raised or lowered, I preferably provide a pair of rods 14 that are preferably threaded into the false bottom 3 of the kier at spaced points thereof and that extend upwardly through suitable openings 15 in the grid 8' to points adjacent to the top 16 of the kier. Thus, the grid 8' will not leave the guide rods 14 when raised to a convenient position for unloading the yarn packages.

For preventing the liquor used for dyeing the yarn packages in the kiers from escaping at the lower end of the perforated tubular yarn holders 5 without passing through the

yarn and at the same time permitting the grid 8' to be raised when desired, I preferably provide the resilient packing discs 17 and the metallic washers 18. The packing 5 discs 17 are preferably secured to the yarn holders 5 at the lower ends thereof and, as shown in Figure 3 of the drawing, are preferably thicker than the grid 8', while the metallic washers 18 are sleeved upon the 10 yarn holders so that they may move with the grid. When the yarn packages are removed from the holders 5 and the grid is lowered, the washers 18 are adapted to rest upon the resilient discs 17 shown in Figure 3 of the 15 drawing, which discs have been received into the opening 10 in the grid. When the yarn packages are sleeved upon the holders 5, the washers 18 supporting the yarn packages on the grid will compress the resilient discs 17 20 as shown in Figure 1 of the drawing, to effect a tight joint at the lower ends of the yarn holders.

In use, when it is desired to remove the 25 yarn on the holders within the kier, the cover 16 of the kier may be swung back on its pivots 19 and the caps 8 detached from the upper ends of the holders 5, whereupon the chains 12 of a suitable hoist may be attached to the eyes 13 of the lifting rods for raising 30 the grid to the desired elevation for unloading the yarn packages, in which case the grid lifts the metal washers 18 and they in turn lift the yarn packages, the packing discs 17 remaining on the bottom of the kier.

35 While it is believed that from the foregoing description the nature and advantages of the invention will be readily apparent, I desire to have it understood that I do not limit myself to what is herein shown and 40 described, and that such changes may be resorted to when desired as fall within the scope of what is claimed.

What I claim as my invention is:

1. In a machine of the class described, the 45 combination with a kier, and yarn holders projecting upwardly from the bottom of the kier, of means in the kier for raising the yarn packages to facilitate the removal thereof from the yarn holders in the kier.

50 2. In a machine of the class described, the combination with a kier, and yarn holders projecting upwardly from the bottom of the kier, of a movable support for the yarn packages in the kier, and means for moving said support to facilitate the removal of the yarn packages from the yarn holders in the kier.

55 3. In a machine of the class described, the combination with a kier and yarn holders 60 projecting upwardly from the bottom of the kier, of means sleeved upon the holders for raising the yarn packages in the kier to facilitate the removal thereof from the kier.

65 4. In a machine of the class described, the combination with a kier, and yarn holders

projecting upwardly from the bottom of the kier, of a member sleeved upon said yarn holders for supporting said yarn packages, and means for raising said member to facilitate the removal of said yarn packages from 70 the kier.

5. In a machine of the class described, the combination with a kier, of perforated tubular yarn holders projecting upwardly from the bottom of the kier, a grid sleeved upon 75 said yarn holders and normally engaging the bottom of the kier, and a lifting member connected to said grid.

6. In a machine of the class described, the combination with a kier, of perforated tubular yarn holders projecting upwardly from the bottom of the kier, a grid sleeved upon 80 said yarn holders and normally engaging the bottom of the grid, means for moving said grid, and means for guiding the movement 85 of said grid.

7. In a machine of the class described, the combination with a kier, of perforated tubular yarn holders projecting upwardly from the bottom of the kier, a grid sleeved upon 90 said yarn holders and normally engaging the bottom of the grid, means for moving said grid, and a rod projecting upwardly from the bottom of the kier for guiding the movement 95 of said grid.

8. In a machine of the class described, the combination with a kier, of tubular yarn holders projecting upwardly from the bottom of the kier, said holders having openings 100 therein for permitting the passage of the liquor used for dyeing the yarn, a movable grid for supporting the yarn sleeved upon said holders and normally engaging the bottom of the kier, and means for preventing the liquor used for dyeing from escaping at the lower ends of the holders without 105 passing through the yarn when the grid is in engagement with the bottom of the kier.

9. In a machine of the class described, the combination with a kier, of tubular yarn holders projecting upwardly from the bottom of the kier, said holders having openings 110 therein for permitting the passage of the liquor used for dyeing the yarn, a movable grid for supporting the yarn sleeved upon the holders and normally engaging the bottom of the kier and means for preventing the liquor used for dyeing from escaping at the lower ends of the holders without 115 passing through the yarn when the grid is in engagement with the bottom of the kier, said means including resilient members surrounding the yarn holders, and washers sleeved upon said holders engageable with 120 said members.

10. In a machine of the class described, the combination with a kier having a true bottom and a false bottom, secured to the 125 true bottom of yarn holders detachably se- 130

cured to said false bottom, and means in the kier for raising the yarn packages off of said yarn holders to facilitate the removal thereof from the kier.

5 11. In a machine of the class described, the combination with a kier having a true bottom and a false bottom secured to said true bottom, of yarn holders secured to said

false bottom, a support for yarn packages sleeved upon said yard holders, and means 10 for actuating said support for raising said packages off of said holders to facilitate the removal of said packages from the kier.

In testimony whereof I affix my signature.

WALTER S. GATES.
